CLAIM

We claim the ornamental design for a fabric waistband garment, as shown and described.

DESCRIPTION

FIG. 1 is a front perspective view of the fabric waistband garment in accordance with the present design.

FIG. 2 is a back perspective view thereof.

FIG. 3 is a front side view thereof.

FIG. 4 is a back side view thereof.

FIG. 5 is a right side view thereof; and,

FIG. 6 is a left side view thereof.

As indicated in the title, the article of manufacture to which the ornamental design has been applied is a fabric waistband garment. An example of a fabric waistband garment is a fabric waistband garment for athletic wear, sports clothing, sports apparel, leggings, sports bras, and/or the like.

The long dashed broken line outline of leggings depict environment associated with the fabric waistband garment and form no part of the claimed design. The short dashed broken lines along the fabric waistband garment depict feature lines that form no part of the claimed design.
